UNITED STATES PATENT OFFICE.

ERNEST C. PFAFF, OF CHICAGO, ILLINOIS.

AUTOMOBILE SPOTLIGHT.

Application filed October 16, 1922. Serial No. 594,677.

To all whom it may concern:

Be it known that I, ERNEST C. PFAFF, a citizen of the United States, residing at Chicago, in the county of Cook and State 5 of Illinois, have invented certain new and useful Improvements in Automobile Spotlights, of which the following is a specification.

This invention which relates to a spotlight 10 for automobiles, is particularly concerned with certain features of construction by which the device is specially adapted for attachment to a closed body, such as the sedan, coupé, etc.

15 It is a principal object of this invention to produce a spot light which can be manufactured and installed at small cost; which is simple in its construction and dependable in its operation; and which may be manipulated from the inside of the vehicle body to direct the light beams in any desired direction.

An exemplification of this invention in a preferred form is illustrated in the accompanying drawing wherein—

25 Figure 1 is a side elevation of the device; and

Figs. 2 and 3 are enlarged vertical sections of the operating parts at each end thereof.

30 It is to be understood that the spot light of my invention, while described in relation to a closed body of an automobile, may be used elsewhere to advantage, and the terminology hereinafter employed should be construed accordingly.

35 The device is shown as mounted upon one of the fixed supports A of the top or wind shield of a closed car body. Through this body support is formed an opening adapted 40 to receive a tubular arm B which extends outwardly to provide a swiveled mounting for the light C. The tubular arm also passes through a plate D secured to the outer side of the body support, and is further held in place with the aid of a bracket E which is fastened to the inner side of the body support. By the means described, viz, the plate and bracket, bearings are provided for the tubular arm B such as to facilitate its 45 rotation, as well as of the other parts which are operatively associated therewith.

At the outer end of the arm is a plug F secured thereto by means of screw threads, or otherwise, in a non-rotatable relation.

50 Mounted upon this plug is a fitting G in the form of a housing equipped with a remov-

able side 7. The housing is shown as having a screw-threaded connection with the plug, but is prevented from rotating thereupon through the medium of a set screw 55 8. Mounted to swivel upon the housing G is an elbow H on which is supported the usual light casing, the elbow being also adapted to accommodate therein a lamp socket 9 into which is fitted the usual electric bulb.

The swiveled connection between the elbow and housing G may take the form of a collar 11 which is screw-threaded into the elbow and extended therefrom through one 70 wall of the housing to present therein a head 12 which is in the form of a beveled pinion. By the use of a set-screw 13 entered through one wall of the elbow the collar is fixedly held against rotation relative thereto. 75

Operatively associated with the beveled pinion 12 is a second pinion 15 carried on the outer end of a tube 16 which is rotatably fitted within the arm B. The pinion 15 is locked to this tube as through the medium of 80 a pair of pins 17 each having a terminal 18 which is slidably received within a slot 19 formed in the tube walls. By this means the tube and pinion 15 are locked non-rotatably, but in such a manner that the tube may be 85 moved in endwise direction within the limits defined by the length of the slots 19.

The inner end of the tube 16 projects a slight distance beyond the corresponding end of the tubular arm B, as clearly shown 90 in Fig. 3. Mounted upon the inner end of the tube 16 is a hand wheel 20 which is locked thereto with the aid of suitable pins 21 which are shown as disposed within recesses in one side of the wheel while effecting a locking engagement with the tube. The recesses wherein the pins lie are faced toward a clutch collar 22 which is locked to the inner tube 16 so as to remain always in juxtaposition to the hand wheel which is 95 further secured in place with the aid of a nut 23. In this collar are fixedly mounted pins 24 which protrude outwardly therefrom to engage within suitable openings formed in a clutch plate 25 that is held fast by 100 screw threads or otherwise upon the end of the arm B, the plate being positioned within a housing 26 which is carried by the bracket E.

Within the housing wherein the clutch 110 plate is accommodated I have provided a spring 27 adapted to exert thereagainst an

inward pressure such as tends to hold the arm B in the position of Fig. 3 with the clutch plate engaging a ring-flange 28 which is fixedly secured to the housing as by screws 5 or otherwise. Fixedly seated in this ring-flange are other pins 29 adapted also to lie within suitable apertures in the clutch plate when the parts are in normal relation.

The nut 28 is properly apertured for the 10 extension therethrough of an electric conductor 30 which traverses the inner tube 16 and the two beveled gears 15 and 12, so as to connect with the socket 9 in which is fitted the usual electric light. In this manner I 15 provide a suitable conductor for the electric circuit required for the operation of the lamp. A device answering to the preceding description is adjustable within wide ranges to any desired position. The operator by 20 properly manipulating the hand wheel 20 is enabled either to swing the elbow upon its pivotal mounting, or to rotate the tubular arm B by which the entire light is swung about a horizontal axis. Either or both of 25 these two movements are effected in the following manner:

To swivel the elbow about its axis, represented as vertical in the drawing, it is necessary to transmit rotary motion through 30 the inner tube 16 and thence through the two beveled gears. As long as the parts remain related as in Fig. 3, this is not possible of accomplishment owing to the fact that the pins 24 remain engaged with the clutch plate 35 which, through the medium of the other pins 29, is locked to a stationary element—the ring-flange. By pulling the hand wheel inwardly, however, i. e., in a direction away from the lamp, the pins 24 are caused to dis- 40 engage from the clutch plate whereupon the hand wheel is free to rotate for the purpose of communicating a like movement to the inner tube 16 and the parts associated therewith. While shifted to this inward position, 45 the hand wheel may accordingly be rotated, as required, to bring about a swiveling movement of the elbow.

A further adjustment in the position of the light may be effected by pushing the 50 hand wheel outwardly, i. e., in a direction toward the light, with the result that the clutch plate is shifted away from engagement with the pins 29. The other pins 24, however, retain a locking connection with 55 the clutch plate such that the hand wheel, when rotated, will transmit a like movement to the tubular arm B, also the inner tube 16, so as to cause the entire housing G to rotate about a horizontal axis. Inasmuch as this movement involves also a like 60 turning of the pinion 15, I avoid relative rotation between the pinion and the arm B such as would otherwise bring about a swiveling of the elbow. With cessation of 65 outward pressure upon the hand wheel, the

spring 27 will return the parts to their normal position, as shown in Fig. 3.

It is contemplated, of course, that a sufficient number of openings will be formed in the clutch plate to receive both sets of pins 24 and 29 in any desired position of rotary adjustment. The form of these openings is of relative unimportance, it being merely sufficient that they act in cooperation with the pins to normally hold 70 the hand wheel against movement.

The advantages of the construction herein described are that the several parts may be readily formed and assembled, and be operated through the medium of a single 75 controlling wheel. The precise form and construction of the several elements which are novel to this invention may, of course, be varied within considerable limits as defined in the claims below.

I claim:

1. In combination with a fixed support having an opening therethrough, a spot light comprising an arm slidably mounted for rotation within the opening and extended away from the support, a bracket in which the arm is journaled, a housing associated with the bracket, a clutch plate mounted fast on the arm and disposed within the housing, stop means against which the clutch plate is adapted to rest, a spring within the housing exerting pressure on the clutch plate such as to hold the latter against the stop means whereby the normal longitudinal position of the arm is determined, a light movably mounted on the outer arm end, an operating wheel having a releasable connection with the clutch plate and adapted both to shift the arm endwise and to rotate the same through the medium of the clutch plate, means for preventing rotation of the clutch plate and arm associated therewith except when the latter is shifted endwise against the tension of the spring, and a further connection between the wheel and the light adapted to move the latter independently of any movement of the arm, substantially as described.

2. A spotlight having in combination a hollow tubular arm mounted for rotation in a fixed support, an inner tube mounted to slide and rotate within the arm, a fitting including a swiveled elbow with light thereon carried by the outer arm end and adapted to be rotated thereby, a connection between the inner tube and swiveled elbow adapted to rotate the latter about its own axis, an operating handle connected to the inner tube at one end, and clutch connections between the tube arm and the support adapted to be made or broken with sliding of the tube within the arm, the clutch connections operating when the parts are in one relative position to lock both the arm and tube against rotary movements, when in another 110 115 120 125 130

relative position to permit rotary movements of only the tube, and when in a third position to permit rotation in unison of both the tube and arm, substantially as described.

- 5 3. A spotlight having in combination a hollow tubular arm mounted for rotation within a fixed support, a fitting carried on the outer arm end and adapted to support a swiveled elbow with light thereon, an
10 inner tube rotatively and slidably mounted within the arm and connected with the swiveled elbow in a manner to rotate the same about its own axis, an operating handle secured fast to the tube at one end and adapted to slide and rotate the same within 15 the arm, a clutch connection between the tube and arm adapted to lock these parts for rotation in unison or to release the tube for rotation independently of the arm, the clutch connection being made or broken 20 with sliding movements of the tube relative to the arm, and spring means tending to hold the tube in a selected position longitudinally of the arm such that the clutch connection is normally maintained.

ERNEST C. PFAFF.
